UNITED STATES PATENT OFFICE

93,362

DESIGN FOR A STORAGE BATTERY CONTAINER

Robert L. Sommerville, Philadelphia, Pa.

Application June 28, 1934, Serial No. 52,379

Term of patent 14 years

To all whom it may concern:

Be it known that I, ROBERT L. SOMMERVILLE, a citizen of the United States, residing at Philadelphia, in the county of Philadelphia and State of Pennsylvania, have invented a new, original, and ornamental Design for Storage Battery Containers, of which the following is a specification, reference being had to the accompanying drawing, forming part thereof.

The side and end portions not shown in the drawing are of the same design as those shown in the drawing.

I claim:

The ornamental design for a storage battery container, as shown and described.

ROBERT L. SOMMERVILLE.
